L. BLOOM

EMBROIDERY MACHINE

Filed Jan. 28, 1924

INVENTOR

LOUIS BLOOM,
by James L. Hopkins, ATTORNEY.

UNITED STATES PATENT OFFICE.

LOUIS BLOOM, OF ST. LOUIS, MISSOURI.

EMBROIDERY MACHINE.

Application filed January 28, 1924. Serial No. 688,968.

To all whom it may concern:

Be it known that I, LOUIS BLOOM, a citizen of the United States of America, residing at the city of St. Louis, in the State of Missouri, have invented certain new and useful Improvements in Embroidery Machines, of which the following is a specification, reference being had therein to the accompanying drawing.

10 My invention relates to improvements in embroidery machines, and has for its object to provide means to feed embroidery thread directly to the machine from the original spools without rewinding, and also to feed 15 simultaneously from a plurality of such spools threads of various colors or the same color.

The attachment of my invention comprises a spool-carrying arm, equipped with spacing collars and secured to the depending spool-holding tension bracket of the embroidery machine by a suitable clamp.

Drawings.

25 In the drawings—

Fig. 1 is an end view of the apparatus of my invention in place upon an embroidery machine.

Fig. 2 is a front elevation of the same.

Description.

The drawings indicate the machine-bed as 3, and depending therefrom are the thread-tube 4 and bracket 5, said bracket 5 carrying 35 the spool-holding pin 6 whereon the secondary spool 7 is mounted. The tension-finger 8 is also empty or carried by the bracket 5 and bears upon the body of the spool 7, serving both to keep the spool 7 on 40 the pin 6 and to maintain pressure upon said spool 7. The bracket 5 also holds the flexible tension-arm 9 provided at its free terminal with the loop 10.

The parts thus described are those of the 45 standard embroidery machine commonly used in the art; and for use upon such machine and as a part thereof, I have provided the extension A, formed as shown in the drawings, its upper terminal 11 being secured to the bracket 5 by means of the clamp 12. The lower terminal of said extension A being the spool-holding rod 13, which is held in parallel alinement with the secondary-spool-holding pin 6.

55 Upon the rod 13 I have provided collars 14 each having a set screw 15, and in the

drawing I have illustrated (Fig. 2) two supply spools 16 mounted upon the rod 13, and there loosely held by two of the collars 14. The rod 13 may be of greater length if desired in order to hold three or more spools 16, of the standard size, upon which the desired thread is vended by the manufacturer. The thread carried by said spools may be of the same or various colors, the object of my construction being to enable the thread from said spools 16 to be fed simultaneously to the machine by being looped over the secondary spool 7, then through the loop 10 and into the tube 4. The thread is operated 70 upon by the machine in the usual manner.

Mode of operation.

In the present use of the embroidery machine for which my attachment is intended, 75 the thread is rewound from the commercial spool 16 to the smaller secondary spool 7 which is used as a part of the machine. When two colors are desired to be simultaneously fed, the thread of those colors is wound from the two original spools 16 upon the secondary spool 7. The capacity of the spool 7 is approximately one-fourth the capacity of the ordinary commercial spool.

It is the primary object of my invention 85 to enable the commercial spool 16 to be used upon the machine without rewinding; and also to enable two or more colors to be fed simultaneously to the machine from such original spools 16.

In the use of the apparatus of my invention, a uniform tension is preserved in each of the several threads being fed from the spools 16, as described.

Variations in structure may be made from 95 the form shown in the illustrations, which is intended to be merely illustrative, without departing from my invention, as it is defined in the following claims.

Claims.

100

1. In an embroidery machine having a spool-holding tension bracket, an auxiliary spool-holding arm; and a clamp securing said arm to said tension bracket; said 105 bracket and arm being arranged to hold an empty spool and a supply spool respectively.

2. In an embroidery machine having a spool-holding tension bracket, the combination of an auxiliary spool-holding arm; adjustable collars mounted on said arm; and a clamp detachably securing said arm to 110

said bracket; said bracket and arm being arranged to hold an empty spool and a supply spool respectively.

3. In an embroidery machine, in combination, a secondary spool; a tension device for said spool; and an arm arranged to hold one or more primary spools in parallel

alignment with said secondary spool, said primary spools being arranged to feed their contents to the machine by way of said secondary spool.

In testimony whereof I have hereunto affixed my signature.

LOUIS BLOOM.
